Primary Examiner — Paula Greene(74) *Attorney, Agent, or Firm* — Michael Rodriguez**CLAIM**

The ornamental design for a communications headset, as shown and described.

DESCRIPTION

FIG. 1 is a front-top-right perspective view of a communications headset showing my new design;

FIG. 2 is a front view thereof;

FIG. 3 is a back view thereof;

FIG. 4 is a right side view thereof;

FIG. 5 is a left side view thereof;

FIG. 6 is a bottom view thereof;

FIG. 7 is a top view thereof;

FIG. 8 is a front-top-right perspective view of a second embodiment showing my new design;

FIG. 9 is a front view thereof;

FIG. 10 is a back view thereof;

FIG. 11 is a right side view thereof;

FIG. 12 is a left side view thereof;

FIG. 13 is a bottom view thereof; and,

FIG. 14 is a top view thereof.

The broken lines showing of the unclaimed environment forms no part of the claimed design.
